UNITED STATES PATENT OFFICE.

DESIGN FOR A STATUE.

55,872.

Specification for Design.

Patented July 20, 1920.

Application filed December 19, 1919. Serial No. 346,188. Term of patent 7 years.

To all whom it may concern:

Be it known that I, PIETRO MONTANA, a subject of the King of Italy, residing in the borough of Brooklyn, county of Kings, city and State of New York, have invented a new, original, and ornamental Design for Statues, of which the following is a specification, reference being had to the accompanying drawing, forming a part thereof.

The drawing indicates a front view of my statue, showing my new design.

My design shows an American soldier in

action, standing on pedestal, left foot extended forward, equipped with a cartridge belt, and a rifle unslung, with fixed bayonet in his left hand, right hand clenched, shirt open at front exposing chest, with head erect. A helmet lies at foot of soldier.

I claim the ornamental design for a statue as shown.

PIETRO MONTANA.
